UNITED STATES PATENT OFFICE.

CHARLES L. KALMBACH, OF RICHMOND, VIRGINIA.

IMPROVEMENT IN METHODS OF TAMPING.

Specification forming part of Letters Patent No. 155,731, dated October 6, 1874; application filed June 24, 1874.

To all whom it may concern:

Be it known that I, CHARLES L. KALMBACH, M. E., of Richmond, in the county of Henrico and State of Virginia, have invented a new and useful Mode of Tamping or Stemming Mines Charged with Nitro-Glycerine or kindred explosives; and I do hereby declare that the following is a full, clear, and exact description of the same, reference being had to the annexed drawing, in which I have shown a mine charged, according to my invention, in vertical section.

The value of tamping a mine before exploding it is well recognized among all engineers; it economizes explosive material and drilling, increases the efficiency of the blast, and tends to reduce the violent projection of the fragments. Heretofore such tamping of mines charged with nitro-glycerine has been too dangerous to be properly performed, or even attempted.

My invention consists in providing an air-cushion between the nitro-glycerine, or similar explosive, and the tamping material, so as to avoid the danger of percussive compression of the charge, while tamping the same, thus ridding that operation of the only and primary cause of premature explosion.

In the annexed drawing I have shown a mine tamped in this manner.

The hole having been bored to the requisite depth, the charge to be exploded is first in-

serted at A, and then the primer B is lowered till it rests well on top of the charge; then a wad, C, of rags, tow, waste, leaves, or similar material, is gently but firmly driven down upon the primer, and covered with a handful or two of sand or dust, to close the interstices. Another similar wad, E, is then driven down, not upon the first one, but so as to leave an air-space of from six inches to a foot between the two wads, as shown at D. Then some ordinary tamping is introduced, which is not very firmly packed, as shown at F, leaving a foot or two of the top of the hole for hard ramming, which may safely be driven with bar and sledge, the air-cushion preventing all blows from affecting the charge below. The fuse or wires H is or are extended out of the hole in the usual manner.

What I claim as my invention, and desire to secure by Letters Patent, is—

The mode of tamping mines charged with nitro-glycerine, or its compounds, by interposing an air-cushion in conjunction with loose and firm tamping, substantially as set forth.

In testimony whereof I have signed my name to this specification in the presence of two subscribing witnesses.

CHARLES L. KALMBACH.
